UNITED STATES PATENT OFFICE.

HEINRICH MÜLLER, OF NUERMBERG, GERMANY.

FABRIC-COVERED TOY FIGURE.

Application filed April 8, 1925, Serial No. 21,732, and in Germany August 22, 1921.

This invention relates to toy figures made of sheet metal and covered with fabric and it relates especially to the manner in which the fabric is fixed on the body of the figure and on the members of the same and to the arrangement which makes it possible to form the several members and to put the same together after the several elements have been covered with fabric.

10 A toy figure and the several elements of which the same is composed are shown, by way of example, on the accompanying drawings in which

15 Fig. 1 shows the toy figure in vertical section. The fabric cover is indicated by dash and dot lines, in the hollow body of the figure a bottle shaped insertion is shown.

Fig. 2 shows in front elevation the body of the toy figure.

20 Fig. 3 is a section on line 3—3 of Fig. 2.

Fig. 4 shows on larger scale means for connecting the edges of the body with one another.

25 Figs. 5 and 6 show the pieces of sheet metal of which the arms and legs are made.

Fig. 7 illustrates the means for fixing the arms or legs.

30 Fig. 8 shows a sheet metal disk serving at the same time for holding together the parts of the body and for attaching the arms.

35 Figs. 9 and 10 show respectively in front elevation and in side elevation the sheet metal blanks for a bear's head.

Figs. 11 and 12 are similar views as Figs. 40 9 and 10 relating to a monkey's head.

Fig. 13 shows the face of a monkey's head in a plane.

Fig. 14 illustrates how an eye is fixed in a bear's head.

45 Fig. 15 shows the sheet metal blank designed to form an ear of a bear's head in front elevation and side elevation and illustrates in which manner it is covered with fabric.

Fig. 16 shows the means for fixing the head rotatably on the body of the figure.

The elements of the toy figure shown in Fig. 1 are: the head 1, the body 2, the arms 3, and the legs 4. These elements are covered with fabric 5 as indicated by dash and dot lines. The body 2 is made from a piece of sheet metal bent so that the edges 6 and 7 are in contact. The edge 6 has pointed teeth 8 designed to engage with slots 10 of flaps 9.

55 At either side of each flap 9 a pointed tooth 12 is arranged. In order to fix the fabric

5 on the body it is put on the pointed teeth 8, placed around the body, hooked on the pointed teeth 12 and pulled over the edge 7 before the two edges are in contact the one with the other. When the edges are made to join the pointed teeth 8 stick through the fabric and penetrate into the slots 10, whereupon they are bent as shown in Fig. 3 to hold the edges together. The ends of teeth 8 are 60 accessible through the open neck end of the body. Owing to the connection by teeth and slotted flaps any shifting of the edges in contact is prevented.

On the upper edge at the neck of the body 70 pointed teeth 11 are arranged over which the fabric is pulled so that it is securely held on the body. These teeth 11 are bent inwardly after the fabric has been put on.

The blanks of sheet metal 3, 4 designed to 75 form the arms and legs have also pointed teeth 13 or 14 on the side edges which are however not to be bent. The teeth on two opposite edges of one blank 3 or 4 are slightly displaced the one with regard to the other 80 and the edge is at the side of each tooth cut out so that two opposite teeth do not come the one in contact with the other nor with the opposite edge when the blank is bent to form an armor leg. Teeth 15 on the lower 85 edge of the blank 3 for the arms do not only serve to hold the edge of the fabric which covers the arm but also a piece 17 of cloth which forms a hand of the figure. The foot end of the blank 4 for the legs has at the 90 point where the heel is situated a pointed tooth 16 serving to hold the edge of the cover of fabric or cloth and for fixing a disk 18 (Fig. 1) which closes the open lower end of the leg and serves as sole.

At the sides of the pointed tooth 16 the edge of the blank 4 is curved inward to form concavities 22 so that, when the tooth 16 has been bent inward it does not project over the edge of the piece 4 of sheet metal 100 but is flush with this edge, the cloth cover being also quite smooth on this edge. The sides 19 of the teeth 8, 16 (Figs. 4 and 6) are approximately parallel to one another and are shaped only at the front ends to 105 form a sharp point whereby the penetrating of the teeth between the threads of the fabric is facilitated and the cloth is prevented from sliding back and getting loose when it has been stripped over the teeth.

110 As the legs and arms are made from bent pieces of sheet metal it is possible to form

the members so that they remain in any desired position without the aid of springs. As the sheet metal blanks after having been bent to form the members tend to expand again they have themselves a spring-like action. As shown in Fig. 7 the arms are fixed on the body by means of an axle 20 which has a rivet head 21 and is inserted through holes of the arm, the rivet head being sunk into a cavity 23 of the outer wall of the arm so that the cloth cover covers this rivet head smoothly.

The axle 20 is preferably straight. If however an element, like the insertion 25 in Fig. 1, is to be inserted into the toy figure the axle 20 of the arms is set off to pass around this insertion. Instead of a set off axle 20 an annular disk 26, shown in Fig. 8 may be used which has a central aperture 27 designed to receive the insertion 25. This annular disk 26 has two opposite arms 28 which form the axle for the arms.

The lateral extensions 28 of the annular disk 26 are bent to semi-circular shape before the arm is put on; they have incisions 29 near their ends. After the arm has been put on the flap 30 of the extensions 28 formed by the incisions 29 are brought into the straight position indicated by dash and dot lines whereby the arm is securely held on the extensions. The annular disk 26 has further rounded teeth 24 on its circumference designed to be inserted through slots in the body whereupon the projecting ends 35 of said teeth are bent over to secure the disk in its position in the body and to securely hold together the two halves of the body.

The sheet metal blank from which the head is made is of a shape corresponding with the shape of the head of the animal to be represented.

Figs. 9 and 10 show, by way of example, the head of a bear. The sheet metal blank comprises two front parts 31 and 32 and a back part 33. Between these parts a front gap 34 and two lateral gaps 35 are arranged which are designed to receive the edges of the cloth cover. The cloth or fabric cover is held on the lower edge of the head by pointed teeth 61. A disk 36 serves to securely hold the parts of the head in position. The disk 36 has extensions 37 to be inserted through slits in the sheet metal of the head. The projecting ends of these extensions 37 are bent over.

The lateral gaps 35 of the head are enlarged at the upper ends 38, said enlargements being designed to receive the ears. As shown in Fig. 15 the ear consists of a piece of cardboard 39 covered with cloth 40. Pointed teeth 41 on the edges of the enlarged part 38 of the slots 35 serve for holding the ear.

In the sheet metal of the head holes 42 for the eyes and holes 43 and 44 are arranged

through which the threads pass which are used for sewing the snout or mouth.

For the monkey's head shown in Figs. 11 and 12 the face, which has no hair, is formed of a separate piece of sheet metal 45 shown in Fig. 13. The sheet metal blank for the head is composed of two front parts 46, 47 and of a back part 48 between which slots 49 and 50 are arranged into which the cloth can be accommodated. A disk 51 in the head serves for holding the parts together and this disk 51 has extensions 52. Two apertures 53 serve to receive the ears. Around the face part 45 a slot 55 is arranged designed to receive the edge of the cloth cover. Pointed teeth 60 on the lower edge of the head serve also to hold the cloth cover. The piece of sheet metal 45 which forms the head is either covered with felt or with wool dust. It is held on the head by means of hook-shaped extensions 56 which are hooked over pointed teeth 57 on the edge of the aperture designed to receive the face. A pointed tooth 58 at the lower end of the face part is bent over the lower edge of the head. A transverse slot 59 is designed to receive the piece of cloth which represents the beard of the animal and which is further pulled over the lower edge of the face part.

The eyes on the monkey's head are formed by a piece of sheet metal 66 on which eyes are painted and which is fixed behind the eye holes 65. A flap 67 on the upper end of the face part serves to securely hold the eye pieces in position.

For a bear figure the eyes 68 shown in Fig. 14 are used. As mounting for the eyes serve two metal tongues 69 which are stuck through the cloth cover 5 and through holes of the wall of the head whereupon they are bent over. The eyes serve at the same time to pull the cloth cover into the sockets of the eyes and to make it fit tightly on the same.

The head can be removably connected with or fixed on the body of the figure. In the toy figure shown in Fig. 1 the head is removable. It is held by the insertion 25. An elastic metal sleeve 70 the lower edge of which is flanged outwards projects through an aperture of disk 36. Flaps 71 cut out of the sheet metal of the sleeve are bent outward after the insertion of the sleeve so that they lay on the disk 36. The sleeve 70 holds the upper end of the insertion 25 and serves at the same time to close the insertion which has the shape of a bottle. The end plate 72 of the sleeve 70 bears on the capsule 73 which closes the bottle shaped insertion. This capsule might also be connected with the sleeve. In the form of construction shown in Fig. 16 the head is rotatably connected with the body so that it cannot be removed. A metal sleeve 74 held in the body

by means of the axle 20 of the arms passing through apertures 75 in the wall of said sleeve, projects into the head. This sleeve 74 is slit in longitudinal direction and has at the upper end a cut out portion 76 in the edge of which incisions 77 are made so that flaps 78 are produced. These flaps are bent outward and grip over the upwardly flanged edge 80 of a horizontal plate 79 fixed in the head. When the head is turned with regard to the body the flaps 78 slide upon the edge 80. As the sleeve is slit it is elastic and fills completely the inner spaces of the body and of the head so that the head is securely held in position.

I claim:

1. A toy figure composed of several elements made of hollow pressed sheet metal representing each a member or part of the figure, and a cloth cover on each of said elements, pointed teeth on the edges of said elements bent inwardly within said hollow elements on which pointed teeth the cloth cover is securely held.

2. A toy figure composed of several elements made of hollow pressed sheet metal representing each a member or part of the figure, pointed teeth on the opposite edges of each sheet metal element said teeth being bent inwardly within said hollow elements and displaced with regard to one another, and a cloth cover for each sheet metal element having its edges clamped between the edges of the sheet metal elements and stuck onto said pointed teeth.

3. A toy figure composed of hollow pressed sheet metal elements representing each a member or part of the figure, pointed teeth on one edge of each element, flaps on the other edge said flaps having each a slot for the reception of the opposite teeth of the adjacent edge so that the edges are held together by the bent over teeth, and a cloth cover on each element the edges of said cloth cover being clamped between two adjacent edges and stuck on said pointed teeth.

4. A toy figure composed of hollow pressed sheet metal elements, representing each a member or part of the figure, pointed teeth on the opposite edges of each element said teeth on one edge being displaced with regard to said teeth on the other edge and cavities at the sides of said teeth so that when the teeth are bent over they are flush with said edges, and a cloth cover on each element clamped between two adjacent edges and securely held by said bent teeth.

5. A toy figure composed of hollow pressed sheet metal elements representing each a member or part of the figure, one of said elements representing the head having slits in its wall, a horizontal disk in this latter hollow-pressed sheet metal element and radial extensions on the circumference of said disk said extensions engaging with

said slits so that when they have been bent over, said sheet metal element is securely held together.

6. In toy figures composed of hollow pressed sheet metal elements representing each a member or part of the figure, cloth covers one for each of said elements, a head made from a hollow pressed piece of sheet metal having slots upwardly extending from the lower edge to separate from one another the several parts of the head said slots being further designed to accommodate the cloth which is in excess of the cloth cover for the head.

7. In toy figures composed of hollow pressed sheet metal elements representing each a member or part of the figure, cloth covers one for each of said elements, a head made from a hollow pressed piece of sheet metal having slots upwardly extending from the lower edge to separate from one another the several parts of the head said slots being further designed to accommodate the cloth of its cover which is in excess, and a face of said head made from a separate piece of sheet metal and surrounded by a slot designed to accommodate the edge of the cloth cover of the face.

8. In toy figures composed of hollow pressed sheet metal elements each element representing a member or part of the figure, cloth covers one for each element, a head made from a hollow pressed piece of sheet metal having slots upwardly extending from the lower edge to separate from one another the several parts of the head said slots being further designed to accommodate the cloth which is in excess, and a face of said head made from a separate piece of sheet metal and surrounded by a slot designed to accommodate the edge of the cloth cover, flaps on the edge of said face part and flaps on the corresponding edge of the head part said flaps of the two edges being located the one above the other the flaps of the face part hooking within the head portion and the flaps of the head part hooking within the face part.

9. In toy figures composed of hollow pressed cloth covered sheet metal elements representing each a member or part of the figure, a cloth cover for each element, a head made from a hollow pressed piece of sheet metal having slots upwardly extending from the lower edge to separate from one another the several parts of the head said slots being further designed to accommodate the cloth which is in excess, a face of said head made from a separate piece of sheet metal and surrounded by a slot designed to accommodate the edge of the head cloth cover and having a slot at the place where the mouth is, flaps on the edge of said face part and flaps on the corresponding edge of the head part said flaps of the two

edges being located the one above the other the flaps of the face part hooking within the head part and the flaps of the head part hooking within the face part, and a piece of cloth to represent the beard inserted into the mouth slot and pulled over the lower portion of the face part.

10. In toy figures composed of hollow pressed cloth covered sheet metal elements representing each a member or part of the figure, a cloth cover for each element, a head made from a hollow pressed piece of sheet metal having slots upwardly extending from the lower edge to separate from one another the several parts of the head said slots being further designed to accommodate the cloth of the head cover which is in excess, and a face of said head made from a separate piece of sheet metal and surrounded by a slot designed to accommodate the edge of the head cloth cover, flaps on the edge of said face part and flaps on the corresponding edge of the head part

said flaps on the two edges being located the one above the other the flaps of the face part hooking within the head part and the flaps of the head part hooking within the face part, a piece of sheet metal having eyes painted on it placed behind the eye holes, and a flap at the upper edge of the face part designed to be bent over inwardly and downwardly to hold said eye piece.

11. A toy figure composed of several elements of hollow pressed cloth covered sheet metal representing the body, the arms, the legs and the head, an insertion piece in said body, and an elastic sleeve in said head, a horizontal annular disk fixed in said head so that it surrounds said sleeve, and flaps outwardly bent from the lower edge of said sleeve resting upon said horizontal disk said sleeve resting on said insertion of the body.

In testimony whereof I affix my signature.

HEINRICH MÜLLER.
